(57) CLAIM

The ornamental design for a game tile protector bag, as shown and described.

DESCRIPTION

FIG. 1 is a front perspective view of a game tile protector bag, showing my new design;

FIG. 2 is a front view thereof;

FIG. 3 is a left side view thereof, the right side view being a mirror image thereof;

FIG. 4 is a top plan view thereof;

FIG. 5 is a bottom plan view thereof; and,

FIG. 6 is a rear view of the game tile protector bag thereof carrying a game tile therein.

The broken line showing of a “game tile” depicts unclaimed environmental subject matter.
